UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,265,278.

Specification of Letters Patent.

Patented May 7, 1918.

Application filed February 12, 1916. Serial No. 77,979.

To all whom it may concern:

Be it known that I, SAMUEL GEORGE TATE, a citizen of the United States, residing at Chicago, in the county of Cook, State of Illinois, have invented certain new and useful Improvements in Presser-Feet for Sewing-Machines, of which the following is a description, reference being had to the accompanying drawing and to the figures of 10 reference marked thereon.

The invention relates to new and useful improvements in a presser foot for sewing machines, and more particularly to a presser foot having a plurality of foot sections 15 adapted to engage the fabric being stitched.

An object of the invention is to provide a presser foot having a shank and main foot sections arranged side by side, which sections are so supported by the shank that one 20 of said sections may move bodily vertically relative to the other, with an auxiliary foot section located intermediate said main foot sections, together with means for supporting said auxiliary foot section whereby the same 25 may move bodily vertically relative to the main foot sections, said auxiliary foot section being so disposed as to engage the en-chained thread loops extending from a stitched article for chaining off when fabric 30 sections are passing beneath the front ends of the main foot sections of the presser foot.

A further object of the invention is to provide a presser foot of the above character with an auxiliary foot section which is located wholly in rear of the needles.

These and other objects will in part be obvious and will in part be hereinafter more fully described.

In the drawings:—

40 Figure 1 is a perspective view of a presser foot embodying the invention and with the strip deflector thrown to one side;

Fig. 2 is a bottom plan view of the same;

45 Fig. 3 is a left hand side view of the presser foot;

Fig. 4 is a top plan view of the presser foot with the strip deflector turned to one side;

50 Fig. 5 is a vertical sectional view through the supporting shank showing the manner of yieldingly supporting the sections of the foot;

55 Fig. 6 is a perspective view of the intermediate yielding sections for engaging the en-chained loops for chaining off;

Fig. 7 is a plan view showing the presser foot and its relation to a cylindrical work support from which the material being stitched is fed off the end thereof.

Fig. 8 is a front view showing the presser 60 foot with the strip deflector turned to one side, also showing the cylindrical work support in dotted lines and also showing the needles and trimmer;

Fig. 9 is a longitudinal sectional view 65 through the presser foot showing one of the side sections and the intermediate section in side elevation, and also showing the needles and the throat plate;

Fig. 10 is a view in section showing the 70 position of the yielding sections of the foot relative to the needles and the fabric sections being joined by the stitching mechanism, the extra thickness of the fabric sections passing under the right hand sections of the 75 foot;

Fig. 11 is a similar view showing the extra 80 ply of fabric passing under the left hand section of the foot; and

Fig. 12 is a view, similar to Fig. 5, but 85 showing a slightly modified form of the invention.

The invention consists in a presser foot which has a supporting shank on which are yieldingly mounted two main foot sections 85 arranged side by side. Between these sections is a third yieldingly mounted section which is located wholly in rear of the needles so as to engage the en-chained loops for chaining off when fabric sections are 90 passing underneath the front end of the presser foot. The two main sections, in front of this intermediate chaining-off section, meet in a line passing between the limits of the stitching mechanism which preferably includes spaced needles so that two fabric sections may have their edges abutted and joined by the stitching mechanism.

Referring more in detail to the drawings, the presser foot consists of a supporting 100 shank 1 having a recess 2 formed therein for receiving the presser bar 3. Extending rearwardly from the shank is an arm 4 which is adapted to engage a guide bar for preventing any lateral movement of the presser foot. Secured to the supporting shank 1 is a main 105 foot section 5. Said foot section 5 is mounted so as to move bodily vertically relative to the supporting shank 1. Said section is formed with a standard 6, see Fig. 5, which 110

freely slides in a recess 7 formed in the shank 1. At the upper end of the standard there is a head 8 which has a threaded connection with the standard 6. This head 8 is slightly larger than the standard 6 and is adapted to engage a shoulder 9 formed in the upper end of the recess 7, to limit the downward movement of the section 5 of the presser foot. A spring 10 is secured to the shank 1 of the presser foot by a suitable screw 11 and this spring bears on the upper end of the head 8 and presses the section downwardly until the head engages the shoulder 9, when the presser foot is raised from the work support.

There is a main foot section 12 which is also bodily movable vertically and yieldingly supported by the shank 1. Said section 12 is formed with an upwardly extending standard 13, see Fig. 5. This standard slides in a recess formed in the side face of the shank 1, and said standard is held in place by a cap plate 14, which covers said recess and is secured to the shank 1 by screws 15.

The standard 13 is slotted, as indicated in dotted lines in Fig. 5, and a screw 16 passing through the slot into the shank limits the downward movement of the foot section 12. A spring 17 is secured to the shank of the presser foot by a suitable screw and, when the foot is lifted, this spring bears against the upper end of the standard 13, and when the foot is lifted it forces the standard downwardly until the upper wall of the slot engages the screw 16. The upward movement of each of the foot sections 5 and 12 is limited by the respective foot section engaging the bottom of the shank 1.

The downward movement of these sections is limited by the means above described when the presser foot as a whole is raised from the fabric.

The foot sections 5 and 12 in the present embodiment of the invention are arranged side by side and are conjointly provided with needle slots 18 and 19. The foot sections meet in a line passing through these needle slots. Projecting into the needle slot 18 is a stitch finger 20. The greater portion of this stitch finger is carried by the foot section 5. Projecting into the needle slot 19 is a stitch finger 21 and practically the whole of this stitch finger is carried by the section 12. The foot section 5 in rear of the tongue 20 is also provided with a curved projecting finger 21* which overlaps the meeting line between the sections and forms the rear wall of the needle slot 18.

Intermediate the main foot sections 5 and 12 is a yieldable auxiliary foot section 22. The inner faces of the main foot sections 5 and 12 are respectively formed with opposed recesses 23 and 24, see Fig. 2, and the intermediate or auxiliary foot section 22 is

located in these opposed recesses. It will be clear from Figs. 2 and 9 of the drawings that this foot section 22 is located entirely in rear of the needle slots 18 and 19 and, therefore, entirely in rear of the needles. The foot section 22 has its front end tapered off at 25. This foot section is carried by a standard 26 which slides in the same recess as the standard 13 of the main foot section 12. Said shank 26 is formed with a slot 27 through which the shank of the screw 16 passes, and this slot limits the downward movement of the section 22. A spring 28 secured to the shank of the presser foot by a screw 29, see Fig. 9, rests on the upper end of the shank 26 and normally forces the foot section 22 downwardly when the presser foot shank is raised. As shown in the drawings, the presser foot is especially adapted for a sewing machine having a cylindrical work support 30 and wherein the position of the presser foot and the feed is such that the materials being stitched are fed off the arm of the machine. A trimming mechanism including a stationary trimming blade 31 and a reciprocating blade 32 may operate upon the edges to be joined and in advance of the stitching mechanism. The stationary blade is carried by the presser foot and the movable blade operates in a recess 32* in the upper face of the presser foot. The trimmed off strip is deflected to one side of the stitching mechanism by a strip deflector 33 which is preferably pivoted to the presser foot so that it may be turned to one side to give access to the needles for threading. This trimmer mechanism and the strip deflector form no part of the present invention.

With the presser foot constructed with needle slots 18 and 19, a stitching mechanism may be used having a pair of needles 34, 34, which enter the needle slot 18, and also a pair of needles 35, 35, which enter the needle slot 19. The outer needles determine the limits of the stitching mechanism and the meeting edges of the foot sections 5 and 12 are located in a line passing between the limits of the stitching mechanism.

As shown in Figs. 10 and 11, the presser foot is especially adapted for the joining of two fabric sections one of which is of a single thickness while the other is of a double thickness, as for example, in the stitching of a folded collarette strip to the body portion of a garment. The folded collarette strip is indicated at S in Fig. 10, and the body portion of the garment is indicated at G.

In Fig. 10 the strip is shown as fed through the machine at the right of the body portion of the garment and the meeting edges of the collarette strip and the body portion of the garment are substantially in line with the meeting edges of the main foot

sections 5 and 12 of the presser foot. It will be noted from this figure that the section 12 yields bodily, permitting the section 5 to engage the body portion of the garment 5 while said section 12 is raised and engages the upper face of the collarette strip. In Fig. 11 of the drawings the collarette strip is shown at the left of the body portion of the garment, in which case the section 5 10 yields and rests against the upper face of the folded collarette strip while the section 12 of the presser foot engages the body portion of the garment. By making both of the sections 5 and 12 so that they may yield 15 bodily, the machine without adjustment may be used for stitching a folded strip at the right of a body portion of fabric or at the left of a body portion of fabric, which ever may be most conveniently according to the 20 garment being operated upon.

When the sections of fabric to be joined are initially fed to the stitching mechanism both sections 5 and 12 will be held off from the work support; one a distance equal to 25 the thickness of the body portion of the garment and the other a distance equal to the thickness of the folded collarette strip. The intermediate section 22 will be forced downwardly by the spring 28 so as to make contact with the enchain threads, and the feeding mechanism will cause the enchain threads to be fed, thus preventing the threads from bunching on the loopers. The projecting finger 21* prevents the threads 30 from being drawn between the meeting edges of the main foot sections. As soon as the sections of fabric reach the intermediate section 22 of the presser foot, said section will be raised, owing to the fact that the forward 35 end of the section 22 is beveled off at 25 and then said section 22 will rest on the folded collarette strip. By locating this chaining off section 22 entirely in rear of the needles, said section will coöperate with the feed in 40 feeding the enchain loops until the fabric sections pass both the needles. After the fabric sections have passed out from under the foot, the section 22 will drop onto the enchain loops.

50 In Fig. 12 of the drawings is shown a modified form of the invention, wherein the left hand section 5 is rigidly connected to the supporting shank 1 and, as shown in the drawings, is formed integral with said supporting shank 1. The presser foot shown in this figure is particularly adapted for stitching wherein the collarette strip is fed to the presser foot at the right hand side of the body fabric in which case it is not necessary 55 that the section 5 should have a yielding connection with the shank of the presser foot. The intermediate section 22 in this form of the invention operates for feeding the enchain loops in precisely the same 60 manner as above described.

In one form of the invention, both the main foot sections are capable of bodily movement relative to the supporting shank, while in the other form of the invention only one of the main foot sections is rigidly carried by the shank and the other has a bodily vertical movement relative to the shank, but it will be noted that in each form of the invention the main foot sections are so supported that one of said sections may move bodily relative to the other, and it is in conjunction with either the one form of the invention or the other that I utilize the auxiliary foot section which is bodily movable vertically and is adapted to engage the enchain loops for the purpose stated.

Having thus described the invention, what is claimed as new is:—

1. A presser foot for sewing machines including in combination, a shank, main foot sections arranged side by side and having opposed recesses, means for supporting said main foot sections whereby one of said sections may move bodily vertically relative to the other, an auxiliary foot section located between the main foot sections in said recesses, and means for yieldingly supporting said auxiliary foot section for bodily vertical movements relative to said main foot sections.

2. A presser foot for sewing machines including in combination, a shank, main foot sections arranged side by side, means for supporting said main foot sections whereby one of the sections may move bodily vertically relative to the other, said main foot sections having a needle slot guide, an auxiliary foot section located between the main foot sections and in rear of the needle slot, and means for yieldingly supporting said auxiliary foot section for bodily vertical movements relative to the main foot sections.

3. A presser foot for sewing machines including in combination, a shank, foot sections arranged side by side and having a needle slot therein, said foot sections meeting in a line passing through said needle slot, means for supporting said foot sections on said shank whereby one of said sections may yield vertically, an intermediate foot section in rear of said needle slot, and means for supporting said intermediate foot section whereby the same may bodily yield vertically for engaging the enchain loops for chaining off when the fabric is passing underneath the forward end of the presser foot, said intermediate foot section having the forward end thereof beveled off to direct the fabric underneath said intermediate foot section.

4. A presser foot for sewing machines including a shank, foot sections arranged side by side, and having a needle slot formed partly in each section, a stitch finger extending into the needle slot and carried by one

of the said sections, an intermediate section located wholly in rear of said needle slot, means for yieldingly supporting one of said first-named sections on said shank, and means for yieldingly supporting said intermediate section on said shank.

5. A presser foot for sewing machines, including a shank, foot sections arranged side by side and having a needle slot formed partly in each section, a stitch finger extending into the needle slot and carried by one of said sections, and a projecting finger carried by one of said sections and overlapping the meeting lines of said sections to form 10 the rear wall of the needle slot.

6. A presser foot for sewing machines, including a supporting shank, foot sections arranged side by side, means for yieldingly supporting each foot section on said shank whereby the same may yield independently 20 of each other, said foot sections having two needle slots arranged one substantially in rear of the other and each needle slot being formed partly in each foot section, a stitch finger carried by one foot section and pro- 25

jecting into one needle slot, and a stitch finger carried by the other section and projecting into the other needle slot, said sections of the foot meeting on a line passing substantially between the stitch fingers. 30

7. A presser foot for sewing machines, including a supporting shank, foot sections arranged side by side, means for yieldingly supporting each foot section on said shank whereby the same may yield independently 35 of each other, said foot sections having two needle slots arranged one substantially in rear of the other and each needle slot being formed partly in each foot section, a stitch finger carried by one foot section and pro- 40

jecting into one needle slot, a stitch finger carried by the other section and projecting into the other needle slot, said sections of the foot meeting on a line passing substantially 45 between the stitch fingers, said foot sections in the rear of the needle slots having opposed recesses and an intermediate foot section located in said opposed recesses.

In testimony whereof, I affix my signature.
SAMUEL GEORGE TATE.
